Patented Aug. 30, 1927.

UNITED STATES PATENT OFFICE.

LOUIS N. COHN, OF ROCK ISLAND, ILLINOIS, ASSIGNOR TO GLEAM MANUFACTURING CO., OF DAVENPORT, IOWA, A CORPORATION OF IOWA.

CLEANING COMPOSITION AND SPOT REMOVER.

No Drawing.

Application filed October 14, 1925. Serial No. 62,466.

Various compositions have heretofore been proposed as cleaning materials, which compositions included, water, soap, soda, turpentine and other substances but these compositions have failed for one reason or another to be entirely satisfactory and I have discovered by extensive experimentation the proper proportions and method of making the substance so that a successful cleaner and spot remover is produced.

Among the objects of my invention are, to improve upon existing cleaning compositions of the character indicated; to so combine the elements of my cleaning composition that there will not be an appreciable excess of any one of them; to develop such a method of making a composition of the kind indicated that an improved product will result therefrom; and such further objects, advantages and capabilities as will hereafter appear and as are inherent in the invention disclosed.

In making this composition, I heat 10 gallons of water to the boiling point and add 5 $\frac{1}{4}$ pounds of chipped soap. A good variety is that sold on the market under the name "Chipso." There is also added 2 $\frac{1}{2}$ pounds of sal soda, 10 ounces of turpentine, 3 ounces of oil of wintergreen and 1 cup of table salt. This mixture is to be stirred well and boiled for two hours. It has been found by experiment that the time of boiling, as well as the ratio of the substances is more or less critical. If the boiling is continued for ten minutes less than two hours the result is not as satisfactory as if the full period is given. Also, an excess of boiling will result in a less satisfactory product.

A chemical reaction seems to take place in the preparation of this product but the nature thereof has not been determined. When properly prepared it is impossible to smell either the turpentine or the oil of wintergreen. These two seem to react with the result that each is eliminated as such, though no chemical tests have been resorted to up to the present time to determine whether or not this is true. It has been found that if the composition is boiled for a substantially less time than that set forth herein a liquid residue will collect upon the top of the paste which is formed when the boiled mixture is poured into cans and let stand. However, if boiled to the proper extent, the paste, when allowed to set will be entirely free from this liquid residue.

This cleaner has been found effective in washing clothes and hands, cleaning tile floors, windows, silverware, kitchen utensils, painted walls and window shades and in removing from wood, fabric, glass, etc., spots such as iodine, ink, grease, and the like.

Having now described my invention,

I claim:

A cleaning composition in the form of a paste the constituent ingredients of which consist of 10 gallons of water, 5 $\frac{1}{4}$ pounds of chipped soap, 2 $\frac{1}{2}$ pounds of sal soda, 10 ounces of turpentine, 3 ounces of oil of wintergreen and one cup of table salt.

In witness whereof, I hereunto subscribe my name to this specification.

LOUIS N. COHN.
